tion of Illinois

Application May 13, 1937, Serial No. 142,387

1 Claim. (Cl. 22—121)

My invention relates, generally, to mould constructions and it has particular relation to the construction of moulds used in the production of composite slabs which may be rolled into various shapes and sizes. This application is a division, in part, of my copending applications, Serial No. 6,497, filed February 14, 1935, now Patent No. 2,145,248, and Serial No. 64,280, filed February 17, 1936.

10 In the bonding and rolling of some high corrosion resistant alloys to steel, the design and type of mould is very essential in making the process commercial and the product usable. Some of the copper alloys, such as silicon copper 15 are particularly fluid in the molten state and are very difficult to hold, in the molten state, on the surface of the steel backing slab. Some of the other non-corrosive alloys, such as the high nickel coppers of from 20% to 40% nickel content, having melting temperatures up to 2400° F., or 20 Monel metal or stainless steel having melting temperatures similar to the steel backing slab, are difficult to hold in the molten state because of the extremely high casting temperatures involved. The mould must be liquid-tight after 25 having been preheated to temperatures of around 2200° F.

Large slabs having a thickness of 10" to 12" must be preheated for five or six hours at this 30 temperature and the mould forming a part thereof must be such that it will not burn out and will remain liquid-tight as a container for the molten flux during the preheating, as well as a container for the non-corroding metal which 35 is cast in the mould after preheating. This casting operation differs from ordinary casting in that the mould, in some cases, is preheated to a temperature above the melting point of the casting alloy and, since the base of the mould 40 or backing member is made up of a relatively thick steel slab, the heat is maintained for a considerable period and the cast metal remains molten much longer than ordinary cast metal remains molten in a cold mould, in which case 45 the cast metal solidifies quickly. In fact, for the cladding of some combinations, such for example as my silicon-copper alloys, it is necessary to prolong the molten state of the casting alloy to perfect a bond between the two.

50 In view of the foregoing, an object of my invention is the provision of a mould which can be rolled as a part of a composite slab either directly from the bonding heat or as soon as the cast metal has solidified and cooled to the maximum hot rolling temperature.

Another object of my invention is to provide an open-faced mould on which the depth can be readily regulated as the measuring means for determining the required thickness of the cast alloy in proportion to the steel backing metal. 5

A further object of my invention is to provide an open-faced mould construction that can be readily adapted to fit any size of slab or backing material.

Another object of my invention is to provide 10 an open-faced mould which may be elongated by working, such as rolling, and which will maintain a uniform rolled edge.

Still another object of my invention is to provide 15 an open-faced mould which will prevent greater elongation of the cast metal than the steel backing metal when the former is softer than the latter.

A still further object of my invention is to so construct an open-faced mould that spreading 20 of the cast metal over the sides of the wrought base metal is prevented when the former is softer than the latter.

Other objects of my invention will, in part, be obvious and in part appear hereinafter. 25

Accordingly, my invention is disclosed in the embodiments hereof shown in the accompanying drawings, and it comprises the features of construction, combination of elements and arrangement of parts which will be exemplified in the 30 description hereinafter set forth and the scope of the application of which will be indicated in the appended claim.

For a more complete understanding of the nature and scope of my invention, reference may 35 be had to the following detailed description, taken in connection with the accompanying drawings, in which:

Figure 1 is a perspective view of one form of mould construction; 40

Figure 2 is a perspective view of a mould construction showing another embodiment of the arrangement of the side members shown in Figure 1;

Figures 3, 4, 5 and 6 show different embodiments of mould construction for producing a composite slab that is arranged to prevent relative spreading between the layer of cladding metal and the slab when the composite slab is rolled; 45

Figure 7 is a perspective view of another embodiment of the mould construction in which the upper surface of the base slab is of channel shape;

Figure 8 is a detail view of a rolling mill show- 55

ing how relative spreading takes place between the slab of base metal and the layer of cladding metal unless special precautions are taken to prevent the same when the cladding metal is 5 relatively soft as compared to the slab metal; and

Figure 9 is a view, similar to Figure 8, showing that no spreading of the layer of cladding metal takes place relative to the slab of base metal 10 when the mould constructions shown in Figures 3, 4, 5 and 6 of the drawings are employed.

The utility and construction of my type of mould for the purpose of cladding by casting one metal on the upper surface of the other, or on 15 this surface in combination with other surfaces, are of great importance. For instance, any size of slab or backing member may be chosen with respect to starting and finish size which best fits the requirements of a particular order or specification with a minimum of scrap loss. This permits using regular bloom sections requiring a minimum of processing before cladding. Generally stated, the mould is formed by welding to the backing slab steel strips or plates of proper 20 height or thickness to govern the mould depth. If the clad slab is to be rolled into plates, for instance, and if the facing or casting alloy has similar compression resistance to the steel backing material, so that they roll evenly, the steel 25 strips are welded to the sides and ends, leaving the full area of the slab for cladding and making a minimum of scrap loss. If the bloom has irregular edges and ends, so that welding along the edges and ends is not practical, the mould 30 strips can be located on the upper surface of the bloom, leaving the irregular ends and edges extending on the outside of the mould strips. It will be understood that the different conditions 35 will govern the particular type of mould construction that is employed.

Referring now particularly to Figure 1 of the drawings, it will be observed that the reference character 20 designates a backing slab, formed, for example, of steel, to the top surface 45 21 of which is to be applied a layer of cladding metal, such as a noncorrosive metal. It is essential that this layer of cladding metal be integrally bonded to the top surface 21 of the backing slab 20 so that the composite slab thus formed 50 may be worked into various shapes and sections. In order to provide this integral bond the cladding metal must be heated to such a temperature that it will become molten. In accordance with the present invention, various embodiments of mould construction may be employed to retain the cladding metal in the molten state so that, on cooling, the composite slab will 55 be formed. It is for this purpose that relatively thin metal side members 22 and relatively thin metal end members 23 are provided around the top surface 21 of the slab 20, are welded together as indicated at 24, and welded to the sides of the slab 20 as indicated at 25.

The cladding metal may be introduced into the 60 mould formed by the side and end members 22 and 23 and the top surface 21, either in the form of a flat plate, or, in the molten state, by pouring. As disclosed in my copending applications, referred to hereinbefore, a suitable flux is provided for excluding air from the bonding surfaces 65 so that no oxidation will take place.

If the composite slab is to be rolled into bars for re-rolling into strip material on which good edges are required for continuous strip rolling, 70 the mould construction shown in Figure 2 may

be employed. As there shown, a layer of cladding metal is to be bonded to the top surface 50 of a slab 51 and a mould is provided therefor by the side members 52 and end members 53. It will be noted that the relatively thin metal side members 52 are located on the upper surface 50 along opposite edges and that they are welded on the outside as indicated at 54. If the slab 51 is from 4" to 5" thick, the side and end members 52 and 53 should be approximately $\frac{1}{2}$ " in 10 thickness to withstand the preheating. With this thickness of side and end members, the side members 52 elongate with the composite slab and, instead of breaking up, finish with a good rolled edge. It will be noted that the end members 53 extend below the top surface 50 of the slab 51 and that they are suitably welded in position. The side and end members 52 and 53 can be welded on the inside of the mould formed by them with the top surface 50 but the weld metal from the arc spatters over the top surface 50 and must be removed before receiving the layer of cladding metal. When the members 52 and 53 are welded on the outside, as shown, they protect the top surface 50 of the slab 25 51 from oxidizing from the heat of the arc.

When the cladding metal is softer than the steel backing member or slab, it is difficult to roll the resulting composite slab, particularly for the first few passes, until the cladding metal 30 or alloy has work-hardened to some extent. As shown in Figure 8 of the drawings, when the composite slab 55 is worked between rolls 56 of a blooming mill, or the like, the softer layer 35 55c of cladding metal elongates faster and further than does the backing metal 55b. This causes the composite slab to curl badly, as shown, and to follow around one of the rolls 56. With a view to correcting this condition the mould 40 constructions shown in Figures 3, 4, 5 and 6 may be employed.

In Figure 3 the top surface 57 of the slab 58 is to be provided with a layer of cladding metal 45 that is appreciably softer than the metal of the base 59. Side members 59, formed of relatively thin metal, are provided along the opposite edges of the top surface 57 and welded thereto as shown at 60. Relatively thick and wide end members 61 are provided at the ends of the top surface 57, between the ends of the side members 59, and are welded in position as shown at 62. On the first pass through the rolls, such as the rolls 56, the relatively thick and wide end members 61 weld to the ends of the top surface 57 so that the end of the composite slab rolls in the 55 same manner as does a solid steel slab, thereby preventing the faster elongation of the cladding metal and the curling of the composite slab, as shown in Figure 8. On a slab 58 approximately 6' long, the end members 61 may be approxi- 60 mately 4" in width.

In Figure 4 of the drawings the mould construction is similar to that shown in Figure 3 except that the side members 59 do not extend the full length of the slab 58. In Figure 5 of the drawings the side members 59 extend below the top surface 57 of the slab 58. Otherwise the construction is as shown in Figure 3.

In Figure 6 of the drawings another form of mould construction is shown in which a slab 65, 70 having a top surface 66 to be clad with a relatively soft cladding metal, is provided with integrally formed side members 67, thereby forming a channel shaped section for receiving the cladding metal. Relatively thick and wide end 75

members 68 are positioned in the ends of the channel section and welded as indicated at 69.

In Figure 9 of the drawings the reference character 72 represents a composite slab that has been formed by the use of one of the mould constructions shown in Figures 3, 4, 5 and 6 of the drawings. It will be observed that no relative spreading or lengthening of the cladding layer 72c with reference to the backing slab 72b takes place. There is, then, no curling, as shown in Figure 8, and a flat rolled section results.

If the cladding metal has substantially the same compression resistance as the backing metal the relatively thick and wide end members 68 may be dispensed with, as shown in Figure 7, while still retaining the channel shaped top section of the backing member 65. Relatively thin metal end members 73 may be welded across the ends of the channel section to form a mould for receiving the cladding metal. A composite slab formed in this manner is particularly well adapted for strip rolling, since the edges roll down evenly with the slab. From the original composite slab rolled into a strip bar, the edges from this type of mould remain square enough for pushing through a pusher furnace and the

edges are suitable for a continuous strip mill.

Since certain further changes may be made in the foregoing mould constructions, and different embodiments of the invention may be made without departing from the scope thereof, it is intended that all matter shown in the accompanying drawings or described hereinbefore shall be interpreted as illustrative and not in a limiting sense.

I claim as my invention:

Means for bonding a relatively thin facing of cuprous metal to a thick heavy backing slab of steel adapted to be reduced by a series of rolling passes according to steel rolling mill practice, which comprises a thick heavy backing slab of steel having a relatively thin steel retaining wall formed of strip steel welded to the slab about the margin of the face to be bonded, said face and said retaining wall forming a fluid tight basin, said face being cleaned and fluxed to facilitate the formation of a bond, the slab with retaining wall and flux being adapted to be preheated to approximately 2200° F. to receive and retain molten cuprous metal for bonding to said face.

THOMAS B. CHACE.
